United States Patent Office

Des. 192,806
Patented May 15, 1962

192,806

TELEPHONE HANDSET

Hans Y. Kraepelien, Los Angeles, Calif., assignor to General Telephone Company of California, a corporation of California

Filed Feb. 9, 1961, Ser. No. 63,880

Term of patent 14 years

(Cl. D26—14)

FIG. 1.

FIG. 2.

FIG. 3.

FIG. 4.

FIG. 5.

FIGURE 1 is a side elevational view showing my design for a telephone handset;

FIGURE 2 is a top plan view thereof;

FIGURE 3 is a bottom plan view thereof;

FIGURE 4 is an end view thereof looking in the direction of the receiver portion; and,

FIGURE 5 is an opposite end view thereof looking in the direction of the transmitter portion.

I claim:

The ornamental design for a telephone handset, substantially as shown.
